UNITED STATES PATENT OFFICE.

CHARLES H. MURRAY, OF ELSWICK WORKS, NEWCASTLE-UPON-TYNE, ENGLAND, ASSIGNOR TO W. G. ARMSTRONG, MITCHELL & CO., (LIMITED,) OF SAME PLACE.

HYDRAULIC MECHANISM FOR OPERATING ORDNANCE.

SPECIFICATION forming part of Letters Patent No. 374,990, dated December 20, 1887.

Application filed May 31, 1887. Serial No. 239,857. (No model.) Patented in Italy December 31, 1886, No. 20,754.

To all whom it may concern:

Be it known that I, CHARLES HENRY MURRAY, a subject of the Queen of Great Britain, residing at the Elswick Works, Newcastle-upon-Tyne, England, engineer, have invented certain new and useful Improved Gear for Guns Fitted with Hydraulic Running-In-and-Out Cylinders, (for which I have received Letters Patent in Italy, No. 20,754, dated December 31, 1886,) of which the following is a specification.

This invention has for its object improved gear for guns fitted with hydraulic running-in-and-out cylinders.

When a gun fitted with hydraulic running-in-and-out cylinders is mounted on a front pivoted slide, it is not easy to make the movement of the gun act upon the valve used for passing the pressure-water to and from the running-in-and-out cylinder, owing to the varying position of this cylinder in relation to the said valve. I therefore introduce additional valve apparatus on the pipe which leads liquid to and from the rear end of the running-in-and-out cylinder, and I arrest the running out of the gun by throttling the passage of liquid under pressure through this pipe to the rear end of the cylinder, and similarly arrest the running in of the gun by throttling the exhaust of liquid through this pipe. The mechanism by which I effect this is shown in the drawings annexed.

Figure 1 is an elevation, partly in section, of a gun and carriage mounted on a front pivoted slide and provided with a hydraulic running-in-and-out cylinder. Fig. 2 is a plan of the slide and carriage with the gun removed. Fig. 3 is a section to a larger scale, showing the additional valve apparatus.

40 a is the gun. b is the carriage. c is the slide, turning about a horizontal axis at its front end, which axis consists of pivots n n, by which the slide is connected with standards n' n', which may be upon a turn-table or be supported otherwise in suitable well-known way.

d is the hydraulic running-in-and-out cylinder. It is fixed upon the slide, and has working with it a piston, d', the piston-rod of which 50 is attached to the carriage b. When the gun

is fired, the recoil is controlled in the ordinary manner by allowing liquid to escape from the rear end of the cylinder past spring relief-valves X into a tank, Y, which is large enough to contain the liquid till it has time to flow 55 away by a waste-pipe. At the same time a valve in the piston allows water to pass to fill the annular space in front of the piston, as is usual.

e is a pipe by which liquid is passed into and 60 from the rear end of the cylinder d to work the gun, and e' is a pipe by which liquid under pressure is admitted to or allowed to pass from the front end of the cylinder. Both pipes are, as shown at Fig. 2, led to the pivot of the slide, 65 and from thence they are connected to the ordinary slide-valve, A, which is provided with the ordinary valve-lever, B, and used for controlling the admission of liquid under pressure either to the one pipe or the other in 70 well-known way. The pipe e is connected at m with the rear portion of the cylinder, and the pipe e' is connected at m' with the front portion thereof.

When the valve is shifted into such a position that liquid under pressure is admitted to the pipe e' and allowed to pass away from the pipe e, the gun is run in; but when the valve is shifted into a position to admit water under pressure to the pipe e the gun is run out. 75

As it would be difficult to arrange for the gun in its movements to control this valve so as at the proper time to arrest the running in or out movement, I, as before stated, introduce additional valve apparatus on the pipe e. This 85 additional valve apparatus is shown separately on a larger scale at Fig. 3. It is composed of a pair of throttle-valves so arranged that the water going to the cylinder tends to shut one valve, f, and lifts and passes the other, g, while 90 on passing back from the cylinder the water lifts and passes the first valve, f, and tends to close the last one, g. A coiled spring, h, is applied to each of these valves, to hold it to its seat when required, and the two springs 95 are connected with a lever, i, one on either side of the fulcrum i' of the lever. The lever of the double throttle-valve, when in its central or normal position, holds these two helical springs h, one resting lightly on each valve. 100

In this position the water is free to pass to or from the cylinder by one or other of the valves.

It will be seen there is one valve to be throttled to check the running out of the gun and one to be throttled to check the running in of the gun.

The throttling action is thus performed: There is a tappet-bar, *k*, carried upon the gun-slide below the gun-carriage. It is provided with a tappet, *k'*, at each end, and made free to slide in its supports. This tappet-bar is attached freely to the lever *i* of the double throttle-valve. On the carriage *b* is a projection, *b'*, which, as the carriage completes its running in or out movement, strikes against one or other of the tappets *k'* and moves the bar *k* endwise. This movement of the bar turns the lever *i* in one or other direction as the gun finishes the last part of its movement either when running in or out. When the tappet-rod, set in motion by the carriage *b*, thus moves the lever *i*, it compresses one or the other of the springs *h*, bringing a gradually-increasing pressure upon the valve *f* or *g*, by which the water is passing, and, as the action continues, finally the water is so throttled that the carriage comes gently to rest.

The springs I make of different strengths. The one for the valve *g*, through which the pressure-water must pass to run the gun out, is made strong enough to hold the valve closed against the highest pressure used, while the spring which acts on the water on its way from

the rear end of the running-in-and-out cylinder needs only to be a light one, as the water is then only exhausting and is at a low pressure.

I claim—

1. The combination of the gun-slide *c*, turning about a horizontal axis at its front end, the carriage running upon the slide, the running-in-and-out cylinder with its piston, the one connected with the slide and the other with the carriage, the pipes *e e'*, admitting liquid to and allowing it to pass from the rear and front portions of the cylinder, and the throttle-valves *f g*, controlled by the gun in its movements, and thereby caused, when necessary, to oppose the flow of liquid into and from the cylinder by the pipe *e*, substantially as described.

2. The combination of the front pivoted gun-slide, *c*, the carriage running upon the slide, the cylinder, the pipes *e e'*, for supplying liquid to the rear and front of the cylinder, the throttle-valves *f* and *g*, checking the flow through these pipes, the springs holding the valves to their seats, and the lever operated by the gun in its movement and compressing the said springs, substantially as described.

C. H. MURRAY.
